(57) **CLAIM**

The ornamental design for a helmet emitter, as shown and described.

DESCRIPTION

FIG. 1 is a perspective view of a helmet emitter showing my new design;

FIG. 2 is a front elevation view thereof;

FIG. 3 is a back elevation view thereof;

FIG. 4 is a top plan view thereof;

FIG. 5 is a bottom plan view thereof;

FIG. 6 is a side elevation view thereof;

FIG. 7 is an opposite side elevation view thereof; and,

FIG. 8 is a perspective view thereof, shown in a used condition

The broken lines in the drawings illustrate features of the article to which the design is applied that form no part of the claim.
